UNITED STATES PATENT OFFICE

GEORGE E. BURNS, OF CENTRAL FALLS, RHODE ISLAND.

DESIGN FOR A RING.

No. 37,848.

Specification for Design.

Patented Feb. 27, 1906.

Application filed January 22, 1906. Serial No. 297,374. Term of patent 7 years.

To all whom it may concern:

Be it known that I, GEORGE E. BURNS, a citizen of the United States, and a resident of Central Falls, county of Providence, State of Rhode Island, have invented a new, original, and ornamental Design for Rings, of which the following is a specification, reference being had to the accompanying drawing, forming part thereof.

The figure is a perspective view of a ring, showing my new design.

I claim—

The ornamental design for ring, as shown.

GEORGE E. BURNS.
